J. M. Peck.

Balance Scales.

Patented May 23, 1836.

(May 23, 1836.)

509

James A. Peck of Lyndon, State of Vermont

Letters Patent,

The schedule referred to in these Letters Patent & making part of the same, containing a description in the words of the said James A. Peck himself of his improvement in the Platform Balance.

Be it known, that J. James A. Peck of the Town of Lyndon, in the County of Caledonia, & State of Vermont, have made a new and useful improvement in the Platform Balance, which is described as follows, reference being had to the annexed drawing of the same making part of this specification. — This Balance consists of a rectangular box or case A, in which are erected four standards B, having arms at the top D, projecting at right angles, which arms are brought to a sharp edge on the top over which are suspended rings C, and in these rings, four in number are suspended the triangular compound levers, F, G, by arms H, projecting from them, formed into knife edges, similar to those just mentioned producing the points d'appui or fulcra of the balance — the bearing points I, of the platform being outside of the points d'appui just mentioned, These levers are of a triangular shape and have two other arms J, with knife edges, resting in the centre of the case & coupled by rings to the end of a third lever, K, placed below, This third lever is straight, and extends thro' the case, to a perpendicular rod L, connecting it with the short end of the steel yard, — having its fulcrum inside of the case near one end formed by two arms M, projecting from the side of the lever with knife edges, such as are in rings connecting with arms, N, also bearing knife edges, projecting from standard O, fixed in the bottom of the case.

The platform being of the second order. The end of the lower outside of the rectangular case is connected with the lower end of the perpendicular rod, by an arm or cross piece with a knife edge suspended in an eye formed at the end of the rod, the upper end of the rod is attached to the short end of the beam or stockyard. The platform is supported upon the four knife edges, of the triangular beam before described on four studs or supports, projecting from the under side of the platform, faced with steel, leaving a cavity in them to receive the knife edges of the beam. The platform instead of moving inside the case projects over it and moves on the outside thereof, having a perpendicular ledge or edge all round projecting downward, on the side of the long end of the stockyard or lever and parallel with it, is a moveable beam, No. 10 Morris graduated for determining the weight.

It is regulated by a spiral spring and screw S, for producing equilibrium in the platform. The stockyard T, is graduated in the usual manner. A large piece of ap-
plied to the stockyard for determining the pounds, a small piece is applied to the beam for determining the ounces.

Operation. The platform being first brought to equilibrium by the piece and moving with the scales and spring the article to be weighed is placed upon the platform, to move the piece along the stockyard till it is balanced at determining the weight in pounds, the ounces being determined by the small piece moving along the moving.

What I claim as my invention and desire to secure by Letters Patent, consists in the method of constructing a platform so as to make it operate, altogether on the outside of the case instead of the inside; in the peculiar arrangement of the beam, so as to bring the bearing points of the platform at the outside of the fulcrum of the triangular beam; and in the method of constructing the
